UNITED STATES PATENT OFFICE.

HARRY T. COONS, OF CLEVELAND, OHIO, ASSIGNOR TO THE CLEVELAND BURIAL CASE COMPANY, OF SAME PLACE.

DESIGN FOR A HANDLE-PLATE FOR COFFINS.

SPECIFICATION forming part of Design No. 30,361, dated March 21, 1899.

Application filed February 10, 1899. Serial No. 705,205. Term of patent 7 years.

To all whom it may concern:

Be it known that I, HARRY T. COONS, a citizen of the United States, residing at Cleveland, in the county of Cuyahoga and State of Ohio, have invented and produced a new and original Design for Handle-Plates for Coffins or Burial-Caskets, of which the following is a specification, reference being had to the accompanying drawings, forming a part thereof.

In the drawings, Figure I is a front side elevation of a handle-plate having my design. Fig. II is a top plan of the plate. Figs. III and IV are opposite end elevations, respectively, of the plate.

My design consists in a forward swell of the central portion of the plate and two sloping surfaces extending from the top and bottom, respectively, of each end of the plate inwardly and forwardly toward the central portion of the plate. The lower part of the central portion of the plate is provided with a hole or opening *a*.

The leading or characteristic feature of the design consists in the handle-plate provided with the five sloping surfaces formed upon

the forward side of the plate. One of the said sloping surfaces *b* is formed midway between the end portions of the plate and extends from the central portion of the plate upwardly and rearwardly toward the upper edge of the plate, and the remaining sloping surfaces are arranged in two pairs *c*, formed at opposite sides, respectively, of the central sloping surface *b*, and the sloping surfaces of each of the said pairs of sloping surfaces are formed, as already indicated, upon an end portion of the plate and extend from the upper edge and lower edge, respectively, of the said end portion inwardly and forwardly toward the central sloping portion *b* of the plate.

What I claim is—

The design for a handle-plate, substantially as herein shown and described.

Signed by me, at Cleveland, Ohio, this 3d day of February, 1899.

HARRY T. COONS.
